US0D1002684S

(12) **United States Design Patent** (10) Patent No.: **US D1,002,684 S**
Lin et al. (45) Date of Patent: ** Oct. 24, 2023

(54) **LASER ENGRAVING MACHINE**

(71) Applicant: **SHENZHEN ATOMSTACK TECHNOLOGIES CO., LTD.**, Shenzhen (CN)

(72) Inventors: **Huigang Lin**, Shenzhen (CN); **Yun He**, Shenzhen (CN); **Zebin Li**, Shenzhen (CN)

(73) Assignee: **SHENZHEN ATOMSTACK TECHNOLOGIES CO., LTD.**, Shenzhen (CN)

(**) Term: **15 Years**

(21) Appl. No.: **29/816,916**

(22) Filed: **Nov. 26, 2021**

(51) LOC (14) Cl. **15-09**

(52) U.S. Cl.

USPC **D15/122; D15/144**

(58) **Field of Classification Search**

USPC D15/122, 127, 144, 144.1, 144.2, 199; D18/34.3, 50, 53, 55, 57

CPC B23K 26/0853; B23K 26/0635; B23K 26/0861; B23K 26/0884; B23K 26/083

See application file for complete search history.

(57) **CLAIM**

The ornamental design for a laser engraving machine, as shown and described.

DESCRIPTION

FIG. 1 is a perspective view of a laser engraving machine showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and, FIG. 10 is an enlarged view of portion 10 shown in FIG. 1.

The dash-dash broken lines in the drawings depict portions of the laser engraving machine that form no part of the claimed design. The dot-dash broken lines in the drawings depict boundaries of the enlarged portions that form no part of the claimed design.
